UNITED STATES PATENT OFFICE.

CHARLES B. LAWTON, OF DETROIT, MICHIGAN.

SUBTERRANEAN BUILDING.

Application filed March 3, 1927. Serial No. 172,307.

In my companion application filed under even date there is disclosed a novel system of sinuous ramps or inclined ways that may be advantageously used in buildings for parking or storing automobiles or other vehicles, also buildings in which there may be vehicular traffic and storage of merchandise.

This invention aims to use practically the same system of ramps or inclined ways in a subterranean building or an underground structure having a superficial roof. On account of real estate in the center of the city being expensive for parking, garage or storage purposes, I aim to locate buildings under parks, public squares, streets or other places upon which buildings cannot be erected. Probably the only valuable space occupied by my building is that used for entrance and exits and these can be located so as not to interfere with pedestrian or vehicular traffic. The same system of ramps which is applicable to a subterranean building may be also embodied in the basement of a surface building if the basement can be used for such purpose, and in all instances the basement or subterranean structures are designed to afford ample foundation and resistance to the great weight to which such structures may be subjected by the storage or movement of vehicles therein.

Briefly described, my subterranean structure includes a plurality of superposed floors underground and some of the floors are of equal area, while others gradually diminish in area so that from some of the uppermost floors towards the lowermost floor there will be a stepped formation by which marginal portions of various floors will be supported by the ground or ground foundations provided therefor. In this manner the weight of the structure in the ground will have a wedging effect precluding any danger of one side of the structure settling or sinking relative to another side. Figuratively speaking the side foundation walls extend under stepped-in side walls of the structure and thus cooperate with bottom foundation walls in safely supporting the subterranean building. In such building the ramps are arranged to afford a maximum parking or storage space for vehicles and merchandise and irrespective of the depth of the building there will be gradual grades for the entrance and exit of vehicles, without any congestion incident to heavy vehicular traffic.

My invention will be hereinafter specifically described and then claimed, and reference will now be had to the drawings, wherein

Figure 1 is a vertical sectional view of the subterranean building in accordance with my invention;

Fig. 2 is a diagrammatic plan illustrating the system of ramps or inclined ways, and

Fig. 3 is a horizontal sectional view taken on the line III—III of Fig. 1.

To put my invention into practice, I select a public piece of ground and obtain a right to construct my building under the ground with the roof 1 of the building a sufficient distance below the surface 2 of the ground to avoid any interference with city sewers, mains or conduits. With the roof at such a depth under the ground the surface of the ground may be tilled, as in the case of a public park, and the natural appearance maintained.

The building is preferably rectangular in plan and includes outer walls 3 and inner walls 4 with said walls perpendicular, and the walls 4 connected by floors 5 sustained by inner zigzag walls 17 which also sustain the roof 1 and the ground on the roof.

The floors 5 will afford large parking or storage areas and the floors may be all of the same area for a desired depth in the ground. For instance, there are shown four floors of equal area and from there on down into the ground the floors gradually diminish in area by having the perpendicular inner and outer side walls of the lowermost floors set in, towards the center of the building, in stepped formation. This is brought about by an arrangement of perpendicular inner and outer walls in which some of the outer walls 3 are directly under some of the inner walls 4 and such stepped formation may be continued downwardly until the lowermost floor has a considerably smaller parking or storing area. Floors of equal area have been designated 5 and from the lowermost floor 5 the floors progressively decrease in area and are designated 6, 7, 8, 9, 10 and 11.

Between the inner and outer walls of all of said floors I arrange sinuous ramps or inclines, some of which are for entrance purposes and others for exit purposes. With the building substantially rectangular there will be two entrance ramps or subways 12 at diagonally opposed corners of the uppermost floor 5, said ramps or subways having a gradual grade from the surface of the ground to the

floor 5. The other diagonally opposed corners of the uppermost floor 5 will have similar ramps or subways 13 for exit purposes, and if the building is constructed under a public park it is obvious that traffic regulations may be such as to provide for vehicles reaching the park by certain streets and in this manner avoid traffic congestion.

From the uppermost floor 5 ramps are arranged 10 for gradual descent to other lower floors and those ramps used for "down" traffic are designated 14 and those for "up" traffic are designated 15.

At the corners of the building and on each floor 15 there are passageways 16 so that a descending or ascending vehicle may pass on to a desired floor.

As the floors decrease in area there is a proportionate decrease in the length of the inner walls 4, consequently a descending vehicle from the sixth floor can readily swing inwardly at one of the passageways 16 and enter the descending ramp between the sixth and seventh floors. Such travel may be continued 25 to the lowermost floor 11, for the reason that there are two "up" ramps at opposite sides of each floor and two "down" ramps at opposite sides of each floor with the ramps continuous from the uppermost floor to the lowermost floor. With proper traffic regulations it becomes necessary for all vehicles to travel around the building, either up or down with all of the "up" vehicles traveling in one direction and all of the "down" vehicles in one 30 direction, thus avoiding confusion particularly when the passageways 16 are designated to indicate the purpose of the ramp adjacent to the passageway.

As in my companion application the zigzag walls 17 cooperate with partitions 18 in forming stalls or compartments in which vehicles or merchandise may be placed. The stalls or compartments are in rows with aisles 19 between the rows and driveways 20 at the ends 45 of the rows and perpendicular with the outermost rows, so that vehicles may be moved about on each floor without interfering with any ramp traffic.

I attach considerable importance to the stepped formation of the lowermost floors of the building for the reason that various floors and side walls of the building may be firmly braced by the ground without any danger of one side of the building settling more than another. This is preferable when there are many floors of like area and particularly if the underground structure forms the basement of a surface building.

In excavating for the underground building there will be a natural stepped or ramp side wall formation approximating forty-five per cent, consequently there is a natural lay of earth on which the building will rest and

no danger of ground pressure or collapse of building walls.

When a small building is to be erected there may be only one "up" ramp and one "down" ramp with possibly two floors of similar area. In all buildings provision will be made for proper drainage and for the passage of water 70 mains or any other underground conduits through the building.

What I claim is:—

1. A subterranean building having floors gradually decreasing in area, and ramps at 75 the marginal edges of said floors with said ramps continuous from the lowermost floor to the uppermost floor.

2. A subterranean building as called for in claim 1, wherein inner and outer walls support 80 said ramps, and walls and partitions afford compartments on each floor.

3. A subterranean building having superposed floors some of which are of equal area and others gradually decreasing in area, and 85 up and down ramps communicating with all of said floors.

4. A subterranean building as called for in claim 3, wherein there are two up ramps and two down ramps with the entrances to said 90 ramps in opposed relation.

5. A subterranean building comprising inner and outer walls, floors between the inner walls, ramps between the inner and outer walls communicating with said floors, some 95 of said outer walls being set under and in continuation of some of said inner walls to decrease the area of some of said floors.

6. A subterranean building comprising inner and outer walls, floors between the inner 100 walls, ramps between the inner and outer walls communicating with said floors, some of said outer and inner walls being inset to afford a stepped lower floor formation for the lower portion of the building.

7. A subterranean building having walled lower floors of stepped formation with ramps at the outer walls of the floors.

8. A subterranean building having floors of unequal area supported from stepped 110 ground, and ramps on the stepped ground, communicating with said floors.

9. A subterranean building having a continuous ramp foundation, and floors communicating with the ramps of the foundation.

10. An excavation having ramp side walls, horizontal floors in the excavation communicating with the ramps of the side walls, and perpendicular walls between said floors.

11. In an excavation of stepped side wall 120 formation, a building having bottom and side walls conforming to the formation of the excavation and providing ramps, and floors in said building communicating with said ramps.

In testimony whereof I affix my signature.
CHARLES B. LAWTON.
